**METHODS AND SYSTEMS ASSOCIATED
WITH DEVELOPING A METAL
DEFORMABLE PACKER**

BACKGROUND INFORMATION

Field of the Disclosure

Examples of the present disclosure relate to a deformable element that is configured to seal across an annulus by deformation. More specifically, embodiments include a deformable element that is configured to flex across an annulus responsive to being introduced to pressure force.

Background

Directional drilling is the practice of drilling non-vertical wells. Horizontal wells tend to be more productive than vertical wells because they allow a single well to reach multiple points of the producing formation across a horizontal axis without the need for additional vertical wells. This makes each well more productive by being able to reach reservoirs across the horizontal axis. While horizontal wells are more productive than conventional wells, horizontal wells are costlier.

Conventionally, casings can be run to the surface which adds an extra cost of casing length. Other methods can include hanging the casing just above the horizontal or deviated section using a packer, a liner hanger, combination of both. Although this can be a cheaper method, it is still expensive and increases operational complexity. Alternative methods include running the casing to the surface, and then intervening with mechanical or chemical cuts to sever the casing at a point above the horizontal section. However, this provides uncertainty about the shape and condition of the severed portion for re-entry purposes.

Furthermore, in re-frac applications or casing-in-casing applications, the original casing can have existing perforations that are connecting to the reservoir. This may cause pressure to be depleted due to production, and a conventional packer to isolate the top sections of the liner may be required to prevent the hydrostatic head from acting on uncured cement. This causes the liner to drop/move and expose the original perforations to new treating pressure. However, conventional packers require significant size/real estate to compensate for the piston needed to activate them.

Accordingly, needs exist for systems and methods associated with a deformable element that is configured to flex across an annulus based on pressure being applied to an inner surface of the deformable element.

SUMMARY

Embodiments disclosed herein describe systems and methods for a tool with a deformable element that is configured to flex across an annulus based on pressure being applied to an inner surface of the deformable element. This may eliminate the need for a significant increase in the outside diameter or decrease in the inner diameter of the tool, which may allow embodiments to occupy smaller spaces while maximizing the internal diameter through the tool. The deformable element may be configured to be positioned within a chamber that is covered by a first rupture disc. The deformable element may include seals, flex joints, and a body. In other embodiments, the rupture disc may be replaced with a check valve or any other temporary barrier.

2

The seals may be positioned on a proximal and distal end of an inner surface of the body against an outer surface of the tool. The inner surface of the tool may be partial seals configured to limit communication from an area between the inner surface of the body and the rest of the chamber without forming an atmospheric chamber, which can be also accomplished through the installation of a check valve. In embodiments, the seal positioned on the proximal or the distal end may be complete.

10 The flex joints may be indentations, grooves, etc. positioned on an outer surface of the deformable element extending towards the inner surface. The flex joints may be configured to create weak points where the deformable element may flex outward across the annulus, which may 15 allow the deformable element to bend but not break. The flex joints may be positioned between the seals. In other embodiments, the flex joints may be outside of the seals, positioned closer to the ends of the deformable element.

The body of the deformable element may extend from a 20 first flex joint to a second flex joint and include two tapered portions and a stem, wherein the stem is positioned between the two tapered portions. The tapered portions may be configured to increase and decrease the diameter across the body to reduce the diameter across the stem, respectively. 25 This may allow for the stem to move from a first position that is in parallel to a central axis of the tool, to a second position that is bowed, flexed, etc. outward across the annulus. The outer surface of the body of the deformable element may be coupled with a compressible, resilient, 30 high-tensile strength material, such as rubber. In other embodiments, the deformable element may not be coupled with any other materials.

In embodiments, responsive to the first rupture disc that isolates the chamber from the inner diameter of the tool being removed, the inner surface of the body may receive a force from the initial rupture and from fluid flowing through the inner diameter of the tool. This may cause the stem to bow outward to increase the distance from the outer diameter of the tool to the inner surface of the body, which may 35 form a seal across the annulus. In embodiments, responsive to decreasing the force against the inner surface of the body, the stem may no longer bow outward and be reset in the direction that is parallel to the central axis of the tool. In other embodiments, responsive to flexing the stem across the 40 annulus, the stem may not fully retract even if the force is no longer being applied to the inner surface of the body due to reaching the plastic yield of the material which makes the stem permanently in a flex position.

These, and other, aspects of the invention will be better 45 appreciated and understood when considered in conjunction with the following description and the accompanying drawings. The following description, while indicating various embodiments of the invention and numerous specific details thereof, is given by way of illustration and not of limitation. Many substitutions, modifications, additions, or rearrangements may be made within the scope of the invention, and the invention includes all such substitutions, modifications, 50 additions, or rearrangements.

BRIEF DESCRIPTION OF THE DRAWINGS

Non-limiting and non-exhaustive embodiments of the present invention are described concerning the following figures, wherein reference numerals refer to like parts throughout the various views unless otherwise specified.

FIG. 1 depicts a tool, according to an embodiment.

FIG. 2 depicts a tool, according to an embodiment.

FIG. 3 depicts a tool, according to an embodiment.

FIG. 4 depicts a method for using a tool, according to an embodiment.

FIG. 5 depicts a method for using a tool, according to an embodiment.

FIG. 6 depicts a tool, according to an embodiment.

FIG. 7 depicts a tool, according to an embodiment.

FIG. 8 depicts a tool, according to an embodiment.

FIG. 9 depicts a tool, according to an embodiment.

Corresponding reference characters indicate corresponding components throughout the several views of the drawings. Skilled artisans will appreciate that elements in the figures are illustrated for simplicity and clarity and have not necessarily been drawn to scale. For example, the dimensions of some of the elements in the figures may be exaggerated relative to other elements to help improve understanding of various embodiments of the present disclosure. Also, common but well-understood elements that are useful or necessary in a commercially feasible embodiment are often not depicted to facilitate a less obstructed view of these various embodiments of the present disclosure.

DETAILED DESCRIPTION

In the following description, numerous specific details are outlined to provide a thorough understanding of the present invention. It will be apparent, however, to one having ordinary skill in the art that the specific detail need not be employed to practice the present invention. In other instances, well-known materials or methods have not been described in detail to avoid obscuring the present invention.

FIG. 1 depicts a tool 100 for sealing an annulus, according to an embodiment. Tool 100 may be used in connection with further elements, as described in U.S. Ser. No. 16/423,367 filed on May 28, 2019, and U.S. Pat. No. 10,400,521 granted on Sep. 3, 2019, which are hereby incorporated by reference in its entirety. More specifically, tool 100 may be configured to seal across an annulus before/after an upper sub-assembly 105 is decoupled from a lower sub-assembly 110 and/or before an inner diameter of tool 100 is in communication with the annulus outside of tool 100. Tool 100 may include upper sub-assembly 105 and lower sub-assembly 110, which may be configured to be run in the hole as an integral unit, and decoupled from each other. Lower sub-assembly 110 may include a first rupture disc 120, deformable element 130, the outer surface 140, and the second rupture disc 150.

First rupture disc 120 may be positioned between an inner diameter of lower sub-assembly 110 and a housing of deformable element 130. The first rupture disc 120 may be configured to be removed after a pressure differential across the first rupture disc 120 is greater than the first pressure threshold. In further embodiments, rupture disc 120 may be formed of dissolvable materials or any other temporary element that is configured to be removed after a predetermined amount of time, temperature, and/or being interfaced with fluids, etc.

Deformable element 130 may be a device formed of rigid materials, such as metal, that is configured to move from a first mode to a second mode. Deformable element 130 may be a continuous piece of ductile material that is configured to be plastically inflated/deformed. Deformable element 130 may be configured to move between the first mode and the second mode after the first rupture disc 120 has been removed, and responsive to fluid creating a force on the inner surface of deformable element 130. The sudden pressure from rupture disc 120 and the flowing fluid may create a force against the inner surface of a deformable element that

is radial from the inner diameter of the tool towards the inner surface of the casing. In the first mode, deformable element 130 may be configured to extend in a direction substantially parallel to a central axis of lower sub-assembly 110. In the second mode, the middle of the deformable element 130 may be configured to flex, bow, etc. outward to seal/choke across an annulus while the ends of the deformable element 130 remain parallel to a central axis of lower sub-assembly 110. Furthermore, in the second mode, the distance between the outer surface 140 of lower sub-assembly 110 and the inner surface of deformable element 130 may increase. In the second mode, the distance between the outer surface 140 of the lower sub-assembly 110 and the inner diameter of the original casing it runs through may decrease. In further embodiments, Deformable element 130 may be formed of a single material, such as steel, or a combination of materials coupled together. The plurality of materials may be coupled together to allow variation in material properties, such as strength, and ductility, or to allow flex points at desired locations based on the mechanical properties of the materials at different locations.

The second rupture disc 150 may be positioned between the inner diameter of the lower sub-assembly and the annulus. Second rupture disc 150 may be configured to be removed after a pressure differential across the second rupture disc 150 is greater than a second pressure threshold, wherein the second pressure threshold is greater than the first pressure threshold. As such, communication to the annulus through a chamber housing second rupture disc 150 may be formed after both first rupture disc 120 and second rupture disc 150 are removed. In further embodiments, the second rupture disc 150 may be formed of dissolvable materials that are configured to be removed after a predetermined amount of time, being interfaced with fluids, etc.

FIG. 2 depicts deformable element 130 in a first mode, according to an embodiment. As depicted in FIG. 2, in the first mode, an outer surface of deformable element 130 may be positioned away from the inner surface of casing 210. Accordingly, in the first mode, fluid may flow between the outer surface of deformable element 130 and casing 210 without restriction. Deformable element 130 may include seals 220, 222, flex joints 230, 232, and a body 250.

The seals 220, 222 may be positioned on a proximal and distal end of an inner surface of the body 250, and be positioned against an outer surface of the tool. The seals 220, 222 may be partial seals configured to limit communication from an area between the inner surface of the body 250 and the rest of the annulus without forming an atmospheric chamber. In embodiments, a first seal 220 positioned on the proximal or the distal end may be a partial seal, while a second seal 222 positioned on the opposite end of body 250 may be a complete seal.

The flex joints 230, 232 may be indentations, grooves, etc. positioned on the outer surface of deformable element 130 and extending towards the inner surface of deformable element 130. Flex joints 230, 232 may be configured to be weak points where deformable element 130 may flex outward across the annulus, which may allow deformable element 130 to bend, yield, or deform but not break. In embodiments, flex joints 230, 232 may be positioned between seals 220, 222. In further embodiments, flex joints 230, 232 may be symmetrical in shape, with a substantial "U-shape." The shape of flex joints 230, 232 may further control the flexing of body 250. In other embodiments, the seals 220, 222 may be positioned between the flex joints 230, 232.

Body 250 may include two tapered portions 240, 242 positioned between flex joints 230, 232, and a stem 252 positioned between tapered portions 240, 242. Tapered portions 240, 242 may decrease the diameter across the metal body 250 to control the flexing of body 250 at stem 252. Due to the decrease in diameter across stem 252 versus that of tapered portions 240, 242, stem 252 may flex more outward than the rest of body 250. In embodiments, weep holes 260, 262, check valves, or one-way valves may be positioned through body 250. The valves may be configured to allow communication from the inner surface of body 250 and the annulus while limiting communication from the annulus to the inner surface of body 250. This may assist in not forming an atmospheric chamber between the inner surface of body 250 and the first rupture disc 120. In other embodiments, the weep holes 260, 262 may be eliminated and an atmospheric chamber can be formed, or the rupture disc 120 and weep holes 260, 262 may be removed so the internal diameter of the deformable element 130 may be exposed to pressure from inside the mandrel 820 or down-hole tool 100. In embodiments, body 250 may have a substantial planar inner surface when run in a hole, wherein the inner surface of body 250 may be configured to be positioned adjacent to the outer surface of a mandrel before body 250 is deformed. Before being deformed, the outer surface of body 250 may have a concave curvature. Once body 250 is deformed, the outer surface of body 250 may have a convex curvature.

In other embodiments, elastic material 253 may be directly coupled, bonded mounted, glued, etc. to an outer surface of the stem 252. Elastic material 253 may extend between tapered portions 240, 242 to 242. Elastic material 253 may be rubber, Teflon, elastomer, or any other elastic material that can deform and seal gaps. Elastic material 253 may be positioned between the first flex joint 230 and the second flex joint 232. In embodiments, elastic material 253 may extend from the first flex joint 230 to the second flex joint 232, or a portion between the first flex joint 230 and the second flex joint 232. In embodiments, elastic material 253 may be rubber, plastic, lower tensile rating steel, or any other material that is softer and more elastic than a material forming the stem 252. FIG. 3 depicts deformable element 130 in a second mode, according to an embodiment. In embodiments, responsive to the first rupture disc being removed, the inner surface of deformable element 130 may be configured to interface with fluid flow, pressure, or both within the inner diameter of the chamber, which may cause a force against the inner surface of deformable element 130. This force may cause deformable element 130 to flex outward, the flex, bow, or deformation may be permanent if it exceeds the max yield strength of deformable element 130.

As depicted in FIG. 3, when the force is applied to the inner surface of deformable element 130, body 250 may begin to flex at the weak points created by flex joints 230, 232, and continue to flex at an increasing angle along tapered portions 240, 242. This may allow the outer surface of body 250 to be positioned adjacent to casing 210. In other embodiments body 250 outer diameter may be coupled to a rubber, elastic element, this may allow body 250 to flex less and allow the outer surface of stem 252 or elastic element 253 to contact the casing 210, which may form a seal across the annulus.

FIG. 4 depicts a method 400 for deforming a tool, according to an embodiment. The operations of method 400 presented below are intended to be illustrative. In some embodiments, method 400 may be accomplished with one or

more additional operations not described, and/or without one or more of the operations discussed. Additionally, the order in which the operations of method 400 are illustrated in FIG. 4 and described below is not intended to be limiting.

5 At operation 410, pressure within a tool may be increased by flowing fluid within a tool.

At operation 420, responsive to the pressure increasing within the tool, the force created by the fluid flowing, the pressure across a first rupture disc being greater than a first pressure differential, etc., the first rupture disc may be removed.

10 At operation 430, the fluid may flow through a chamber housing the first rupture disc and interact with the inner surface of a deformable element.

15 At operation 440, responsive to the fluid interacting with the inner surface of the deformable element, the deformable element may flex at flex joints and across tapered portions of the deformable element. By controlling the diameter across 20 the deformable element at various locations, the outward flex of the deformable element may be controlled to flex but not break, wherein the deformable element may flex across an annulus such that an outer surface of the deformable element is positioned adjacent to the inner diameter of the casing.

25 At operation 450, the pressure within the tool may further increase.

At operation 460, responsive to the pressure within the tool increasing further, a second rupture disc may be 30 removed. This may allow communication through a housing initially holding the second rupture disc, wherein communication is allowed between the inner diameter of the tool and the annulus.

35 FIG. 5 depicts a method 500 for deforming a tool, according to an embodiment. The operations of method 400 presented below are intended to be illustrative. In some embodiments, method 500 may be accomplished with one or more additional operations not described, and/or without one or more of the operations discussed. Additionally, the 40 order in which the operations of method 500 are illustrated in FIG. 5 and described below is not intended to be limiting.

45 At operation 510, a tool may be positioned downhole within a cased hole or an open hole. The cased hole may be positioned downhole within a geological formation that has already been produced and includes fractures that are created by a perforation gun. In another embodiment, the geological formation may be not produced at the time of the position of the tool.

50 At operation 520, cement may be pumped through the tool, followed by a wiper plug. This may force the cement to fill up an annulus positioned between the outer diameter of the tool and the inner diameter of the cased hole. However, there may be a hydrostatic head creating pressure on the upper surface of the cement that is not cured. Without 55 any further forces impacting the cement, this hydrostatic head may force the well to drink and move the cement downhole, which may not allow the cement to be cured at the desired locations.

56 At operation 530, a deformable element may expand across the annulus at a location above the upper surface of the cement. By expanding the deformable element, the deformable element may create a sufficient force to isolate the annulus above from the annulus below, which prevents the hydrostatic head from acting on the cement head or set packers, it may be necessary to deform existing materials at a kickoff point to form the seal to limit the real estate required for elements in a narrower casing.

At operation 540, the cement below the deformable element may cure. By expanding the deformable element above the upper surface of the cement in a refracturing operation, the cement may not drop downhole due to the hydrostatic head applying forces against the upper surface of the cement.

FIG. 6 depicts a deformable body 600, according to an embodiment. Elements depicted in FIG. 6 may be described above, and for the sake of brevity, a further description of these elements is omitted.

As depicted in FIG. 6 deformable body 600 may include an asymmetric flex joint 605. Flex joint 605 may include two asymmetrical curves 620, 630 with a lower sidewall that is tapered 610. This may allow for the deformation of deformable body 600 to occur at lower stresses in a given direction than when compared to a symmetrical flex joint 605.

FIG. 7 depicts a system 700 configured to deform across an annulus to contact an inner surface of casing 710, according to an embodiment. Elements depicted in FIG. 7 may be described above, and for the sake of brevity, a further description of these elements is omitted. System 700 may include a retaining body 720 and a deformable element 705.

Retaining body 720 may include a seal 740 and 730, wherein ledge 730 may be an outcrop, projection, etc. In embodiments, seal 740 may be configured to be positioned adjacent to the outer diameter of a tool, while ledge 730 may be positioned away from the outer diameter of the tool. An end 707 of a deformable element 705 may be configured to be positioned between ledge 730 and the outer diameter of the tool, and be secured between an inner surface of ledge 730 and the outer diameter of the tool. End 707 of deformable element 705 may be free to slide between the inner surface of ledge 730 and the outer diameter of the tool, such deformable element may move along a limited linear path based on the length of ledge 730. Further, due to deformable element 705 deforming in a concave shape, the end 707 may expand and touch/seal on the ledge 730. One skilled in the art may appreciate that both ends of deformable element 705 may be free to slide between the inner surface of a corresponding ledge and the corresponding outer diameter of the tool. Responsive to the inner surface of deformable element 705 receiving a force to deform, deformable element 705 may flex outward to seal across the annulus to be positioned adjacent to casing 710. When flexed across the annulus, the end 707 of the deformable body 705 may remain positioned between ledge 730 and the outer diameter of the tool.

FIG. 8 depicts a system 800 configured to deform across an annulus to contact an inner surface of the casing, according to an embodiment. Elements depicted in FIG. 8 may be described above, and for the sake of brevity, a further description of these elements is omitted. System 800 may include a deformable element 810, rupture disc 815, mandrel 820 with ledge 825, seals 830, and ports 840.

Deformable element 810 may be configured to be positioned within mandrel 820, wherein at least a portion of the upper surface of deformable element 810 is exposed to an annulus. This portion of the upper surface of the deformable element may be configured to flex across the annulus to seal the annulus. The ends of deformable element 810 may be configured to be encompassed and secured in place by mandrel 820 and the ledge 825 of the mandrel.

Seals 830 may be positioned between the lower surface of deformable element 810 and mandrel 820, wherein seals 830 may be configured to limit communication between the inner diameter of system 800 and the lower surface of deformable element 810. In other embodiments, the seals

may be configured on the deformable element 810, the ledge 825, or next to the element proximal end and distal end.

Ports 840 may be configured to allow communication from an inner diameter of system 800 towards a lower surface of deformable element 810. The communication may assist in flexing deformable element 810 across the annulus after rupture disc 815 is removed. In another embodiment, the rupture disc may be replaced with a hole.

FIG. 9 depicts a system 900 configured to deform across an annulus to contact an inner surface of the casing, according to an embodiment. Elements depicted in FIG. 9 may be described above, and for the sake of brevity, a further description of these elements is omitted. System 900 may include a mandrel 910, first retaining body 920, second retaining body 930, first piston 940, second piston 950, and deformable element 960.

Mandrel 910 may be a cylindrical body may include a hollow interior, wherein fluid is configured to run through the hollow interior of mandrel 910. In embodiments, mandrel 910 may be part of a sub-assembly for oil and gas operations. Mandrel 912 may include a first opening 912, second opening 914, and a third opening 916.

First opening 912 may be a first passageway from an inner diameter of mandrel 910 to an outer diameter of mandrel 910. First opening 912 may be a first port that is configured to allow communication from an inner diameter of mandrel 910 towards a first surface of first piston 940. The communication may assist in creating a first piston force against deformable element 960. In another embodiment, first opening 912 may include a rupture disc.

Second opening 914 may be a second passageway from an inner diameter of mandrel 910 to an outer diameter of mandrel 910. Second opening 914 may be a second port that is configured to allow communication from an inner diameter of mandrel 910 towards a first surface of second piston 950. The communication may assist in creating a second piston force against deformable element 960. In another embodiment, second opening 914 may include a rupture disc.

Third opening 916 may be a third passageway from an inner diameter of mandrel 910 to an outer diameter of mandrel 910. Third opening 916 may be a third port that is configured to allow communication from an inner diameter of mandrel 910 towards an inner surface of deformable element 960. The communication may assist in creating an outward force against deformable element 960 to radially expand deformable element 960. In another embodiment, the second opening 914 may include a rupture disc 918. Rupture disc 918 may be configured to be removed after a pressure differential across the rupture disc 918 is greater than the first pressure threshold. In further embodiments, disc 918 may be a temporary disc formed of dissolvable materials or any other temporary element that is configured to be removed after a predetermined amount of time, temperature, and/or being interfaced with fluids, etc.

First retaining body 920 may be a mandrel with a ledge 922 positioned on an outer diameter of mandrel 910. First retaining body 920 may be configured to be fixed in place at a first location. First retaining body 920 may have a first portion with a first thickness, and ledge 922 with a second thickness. The first portion of first retaining body 920 may be configured to end before first opening 912, and ledge 922 may extend over first opening 912 and first piston 940. An end of first piston 940 may be configured to be positioned between ledge 922 and the outer diameter of mandrel 910. Ledge 922 may be configured to radially secure first piston 940 in place while allowing first piston 940 to freely slide in

a linear direction and or expand below it, wherein the linear direction may be in parallel to a central axis of mandrel 910. In embodiments, a shear pin 924 may be added and configured to initially couple ledge 922 and first piston 940 together. Before activating shear pin 924, first piston 940 may not be able to linearly slide between ledge 922 and mandrel 910. After activating shear pin 924, shear pin 924 may break and allow first piston 940 to linearly slide between ledge 922 and mandrel 910. In embodiments, shear pin 924 may be activated and responsive to deformable element 960 radially expanding, wherein when deformable element 960 radially expands the ends of deformable element may be positioned closer together compared to when run in hole.

Second retaining body 930 may be a mandrel with a ledge 932 positioned on an outer diameter of mandrel 910. Second retaining body 930 may be configured to be fixed in place at a second location, which may be downhole from first retaining body 920. Second retaining body 930 may have a first portion with a first thickness, and ledge 932 with a second thickness. The first portion of second retaining body 930 may be configured to begin after second opening 914, and ledge 932 may extend over second opening 914 and first piston 940. An end of second position 950 may be configured to be positioned between ledge 932 and the outer diameter of mandrel 910. Ledge 932 may be configured to radially secure second piston 950 in place while allowing second piston 950 to freely slide in a linear direction and or expand below it, wherein the linear direction may be in parallel to a central axis of mandrel 910. In embodiments, a shear pin 934 may be added and configured to initially couple ledge 932 and second piston 950 together. Before activating shear pin 934, second piston 950 may not be able to linearly slide between ledge 932 and mandrel 910. After activating shear pin 934, shear pin 934 may break and allow second piston 950 to linearly slide between ledge 932 and mandrel 910. In embodiments, shear pin 934 may be activated and responsive to deformable element 960 radially expanding.

First piston 940 may be a device that is configured to exert a force against a proximal end 942 of deformable element 960 to assist in maintaining deformable element 960 in a deformed position. This force exerted by first piston 940 against deformable element 960 may prevent deformable element 960 from collapsing. In embodiments, a first end of first piston 940 may be in communication with pressure within the hollow chamber of mandrel 910 via first opening 912. This communication may expose the first end of first piston 940 to the pressures within an inner diameter of mandrel 910, and allow piston 940 to move in a first, downhole, direction. In embodiments, first piston 940 may include a ratchet, or other locking mechanism, that may not allow first piston 940 to travel in a second, uphole, direction.

A second end 942 of first piston 940 may be configured to interface with a proximal end of deformable element 960. Second end 942 may be angled, such that when deformable element 960 radially expands and deforms, a surface area between first piston 940 and deformable element 960 may increase to assist in maintaining deformable element 960 in the deformed, expanded position. In certain embodiments, second end 942 may be a ramp surface, triangular shaped, etc. In further embodiments, when run in hole the interface between second end 942 and the proximal end 962 of deformable element 960 may be axially between ledges 922, 932.

Second piston 950 may be a device that is configured to exert a force against a distal end 964 of deformable element

960 to assist in maintaining deformable element 960 in a deformed position. This force exerted by second piston 950 against deformable element 960 may prevent deformable element 960 from collapsing. In embodiments, a second end 5 of second piston 950 may be in communication with pressure within the hollow chamber of mandrel 910 via second opening 914. This communication may expose the second end of second piston 950 to the pressures within an inner diameter of mandrel 910. In embodiments, second piston 10 950 may include a ratchet, or other locking mechanism, that may not allow second piston 950 to travel in the first direction.

In other embodiment piston 940 and piston 950 may be integral part of deformable element 960 and made out of one piece

15 A first end 952 of second piston 950 may be configured to interface with a distal end 964 of deformable element 960. First end 952 may be angled, such that when deformable element 960 radially expands and deforms, a surface area 20 between second piston 950 and deformable element 960 may increase to maintain the deformable element 960 in an deformed, expanded position. In certain embodiments, first end 952 may be a ramp surface, triangular shaped, etc. In further embodiments, when run in hole the interface between 25 first end 952 and the distal end 964 of deformable element 960 may be axially between ledges 922, 932.

Reference throughout this specification to "one embodiment", "an embodiment", "one example" or "an example" means that a particular feature, structure, or characteristic 30 described in connection with the embodiment or example is included in at least one embodiment of the present invention. Thus, appearances of the phrases "in one embodiment", "in an embodiment", "one example" or "an example" in various places throughout this specification are not necessarily all 35 referring to the same embodiment or example. Furthermore, the particular features, structures, or characteristics may be combined in any suitable combinations and/or sub-combinations in one or more embodiments or examples. In addition, it is appreciated that the figures provided herewith are 40 for explanation purposes to persons ordinarily skilled in the art and that the drawings are not necessarily drawn to scale.

Although the present technology has been described in detail for illustration based on what is currently considered to be the most practical and preferred implementations, it is 45 to be understood that such detail is solely for that purpose and that the technology is not limited to the disclosed implementations, but, on the contrary, is intended to cover modifications and equivalent arrangements that are within the spirit and scope of the appended claims. For example, it is to be understood that the present technology contemplates that, to the extent possible, one or more features of any implementation can be combined with one or more features of any other implementation.

What is claimed is:

1. A downhole tool for zonal isolation comprising:
a mandrel with a first opening;
a first retaining body with a first ledge, the first opening being aligned with the first ledge;
a permanently deformable element formed of metal configured to transition from a run in hole position to a deformed position, a first end of the permanently deformable element being positioned radially between and under the first ledge and the mandrel, wherein the first end of the permanently deformable element is configured to receive forces via the first opening to act as a piston to assist in maintaining the permanently deformable element in the deformed position, an outer

11**12**

diameter of the permanently deformable element being smaller than the outer diameter of the first ledge before the permanently deformable element is in the deformed position, wherein the first opening permits fluid pressure from an internal diameter of the mandrel to apply 5 a force directly to the first end of the deformable element to assist in maintaining it in an energized state.

2. The downhole tool of claim 1, wherein a first end of the piston remains under the first ledge after the permanently deformable element is radially expanded. 10

3. The downhole tool of claim 2, wherein a second end of the piston is positioned axially between the first ledge and a second ledge.

4. The downhole tool of claim 3, further comprising: a second opening within the mandrel configured to allow 15 communication to the second end.

5. The downhole tool of claim 1, further comprising: A seal positioned between an inner diameter of the deformable element and the mandrel.

6. The downhole tool of claim 1, further comprising: 20 a port configured to be aligned with a center of the permanently deformable element, the port being configured to allow a pressure within the mandrel to be communicated to an inner surface of the permanently deformable element to radially expand the permanently 25 deformable element.

7. The downhole tool of claim 6, wherein the pressure communicated through the port is used to radially expand the permanently deformable element, and the first end applies the first force in a first direction responsive to 30 radially expanding the permanently deformable element.
